PAPER RADIATOR SHIELD

Ben Altheimer, University City, Mo., assignor to
Myrtle Altheimer, University City, Mo.

Application September 28, 1931, Serial No. 565,607

4 Claims. (Cl. 93—1)

My invention relates to improvements in paper radiator shields, and more particularly to a method of making the same to produce such shields which shall be neat and attractive in appearance, simple in construction and with the minimum amount of handling during the process of manufacture, which may be made economically and speedily, and which shall be efficient and satisfactory for use wherever found applicable.

One of the principal objects of my invention is the production of a radiator shield of the kind described, which may be folded to the radiator-conforming shape and which will retain its desired shape with the minimum application of adhesive thereto.

Many other objects and advantages of the method and construction herein shown and described, will be obvious to those skilled in the art to which this invention appertains, from the disclosures herein given.

To this end, my invention consists in the novel construction, arrangement and combination of parts, and the method employed in the production of the same, as shown and described, and more particularly pointed out in the claims.

In the drawings, wherein like reference characters indicate like or corresponding parts throughout the views,

Figure 1 is an elevation view of one of my shields ready for placement upon a radiator;

Figure 2 shows a vertical section of the same, as mounted upon the radiator;

Figure 3 is a fragmentary perspective view of the top portion of the shield;

Figure 4 is a plan view of the blank, ready for folding; and

Figures 5—10 illustrate the various stages of folding.

Referring more particularly to the drawings, wherein I have illustrated a preferred embodiment of my invention, R indicates a radiator of more or less standard type and construction, and upon which my shield or cover S is to be removably mounted. In carrying out my invention, I make these radiator shields or covers of a fairly cheap, relatively thin flexible material such as paper, cloth or the like, it being understood of course, that this material should not be

too flimsy to hold the shape into which it has been formed during the process of folding. Also, that this material should preferably be impervious to the passage of dust therethrough, and tough enough to withstand handling during its

manufacture and in actual service as a radiator shield.

Such a sheet of paper is of generally rectangular shape, and is marked or scored in any desired manner so as to facilitate the folding operations thereupon. The shield is formed of sufficient size to receive the top portion of the radiator therein and to depend downwardly therefrom, the top of the shield being indicated at A, and provided with a pair of side walls B—B at 10 either side of the radiator, and with a connecting rear wall C, the side walls being narrower toward their bottom if desired, and as shown.

The top of the shield is provided with a downwardly extending flange along the front edge of 15 the top, as at 1, this flange being extended rearwardly at either side as at 2—2, to thereby define the radiator-receiving opening. A dust trap is provided by the inwardly directed and thence angularly upwardly flanges 3 and 4 respectively 20 at the lower edge of the front flange 1.

The shield is made of a single sheet of paper or other similarly flexible and cheap material suitable for the purpose, and the same may be plain, or may be colored, decorated, or otherwise ornamented in any suitable manner either before or after the forming thereof.

This blank is of generally rectangular shape or outline, with the top and bottom edges 6 and 7 respectively parallel, and the latter edge preferably slightly shorter than the top edge, in the form shown in the drawings. The side edges 8—8 are at right angles to the top and the bottom edges for a predetermined distance, and are thence inclined inwardly toward one another as at 9—9 to the bottom edge 7.

Intermediate the top and bottom edges of the sheet are a plurality of parallel and predeterminedly spaced horizontal lines of fold 10, 11, 12, 13, and 14, as indicated. These may actually be scored lines or otherwise indicated, for the purpose of facilitating the folding of the shield during the making of the same.

Each of the upper corners of the sheet may be provided with a narrow cut-out 15 indicated by the dotted lines thereat, or the same function may be had by slitting the sheet for a short distance downwardly and the part 15 then bent by doubling the slit portion onto the sheet. This sheet of paper is preferably laid flat upon some supporting plane and the lower portion may then be bent back upon itself along the line 14, thus bringing the lower edge 7 adjacent the line 13, as shown in dotted lines in Fig. 5.

The top edge of the sheet is then brought 55

down onto the body of the sheet by folding along the lines 10 and 12, in the direction opposite to the folding of the lower portion of the sheet, this folded portion along the line 10 forming the 5 flange 4 of the dust trap.

Each of the upper corners of the sheet is then folded toward one another, as shown in Fig. 6, 10 along the diagonal lines of fold 16—16, so as to bring the upper portions of the side edges 8—8 horizontal. Each of these corners is then lifted 15 up, as shown in Fig. 7, so that the previously folded edges 10 will form an upstanding continuous channel or corner above the plane of the sheet, the ends of the channel coinciding with the lines of vertical fold 17—17 inwardly 20 of the side edges of the sheet and parallel thereto.

The next step consists in flattening the aforementioned upstanding channel, by folding the 25 same onto the face of the sheet, as indicated in Fig. 8, this folding at either end being along the top portion of the diagonal line 16.

The previously folded lower portion of the sheet is then folded diagonally along the lines 25 18—18, this diagonal line of fold intersecting the side edge of the sheet a slight distance above the bottom of the previously folded upper portion of the side edge 8, the first fold along the diagonal lines 18 being indicated in Fig. 8 (at 30 the right-hand side), and the second similar fold being completed and shown in Fig. 9, and there is now a triangular tab defined between the lines of fold 17 and that portion projecting laterally to either side of the sheet and indicated at 5—5.

The top of the shield is practically completed, except that some means must be provided for holding its position, and to this end I apply a 40 suitable adhesive to each of these triangular tabs and thence fold them down onto the body of the sheet, this single application of the adhesive being sufficient to secure the various parts together at the areas shown as 20 in Figs. 8 and 9. If desired, staples, stitching or other securing 45 means may be applied instead of the adhesive hereinbefore mentioned, for securing the parts together.

Due to the fact that the diagonal lines of fold 50 18 extend above the bottom edge of the horizontally extended side edges 8 (see Fig. 8, left-hand side, also Figs. 6 and 7) the superimposed continuation of this vertical edge 8 will be above or past the tip or apex of the triangular tab (see right-hand side of Fig. 8). This superimposed 55 edge 8 extends horizontally to the line 17 at the base of the triangular tab and thence extends obliquely past and overlapping the lower free edge of the portion 2 of the shield (see Fig. 8, right-hand side).

As hereinbefore stated, the adhesive is applied 60 as indicated in the shaded areas of the tabs 5—5, whereupon the tabs may be folded down until the adhesive has set. This is the only application of the adhesive during the entire manufacture 65 of the shield, and consequently there is little or no loss of time in waiting for the adhesive to dry before continuing with further operations of making the shield.

The vertically extending distance defining the 70 area of the adhesive 20 is greater toward the base of the tab than adjacent the apex, so that the adhesive will cover only the desired surfaces, and whereby the front flange 1 and the dust trap flanges 4 and 3 will be free of securement to

these tabs, so that the shield may be fully and properly unfolded for use when desired.

In order to further compact the shield, the same is folded along the lines 13 and 21, and the lower tip then inserted beneath the front forming portion of the shield, as shown in Fig. 10. Thus the resultant product is neat and compact, and well adapted for shipping, storage, or other handling, and upon opening will present an attractive appearance for use upon a radiator.

Having thus described my invention, it is obvious that various immaterial modifications may be made in the same without departing from the spirit of my invention; hence I do not wish to be understood as limiting myself to the exact form, arrangement, construction and combination of parts herein shown and described or the method employed, except as limited by the state of the art to which this invention appertains, or the claims hereto appended.

What I claim as new and desire to secure by Letters Patent is:

1. The method of forming a radiator shield, comprising taking a substantially rectangular sheet of material and folding it on itself along the top edge; folding diagonally at each of the corners of said end to form triangular portions; folding said triangular portions to bring said uppermost fold into a vertical plane; folding said last-mentioned edge downwardly along a line parallel to said top edge, while re-folding the upper upstanding edge along the first diagonal line of fold; folding diagonally from the bottom of the sheet to form tabs projecting laterally at the sides of the top of said sheet; and securing the various parts of the shield together by securing said tabs against said previously folded portions.

2. The method of forming a paper radiator shield, comprising folding the top and bottom edges of the sheet parallel to one another and in opposite directions; folding the upper corners diagonally inwardly toward one another to form triangular portions thereat; folding the upper portions of said triangular portions above the plane of the sheet and thence folding the same laterally downwardly along a diagonal line at each end; folding the lower corners of the folded sheet diagonally to overlap the triangular portions and form tabs; and then securing said tabs onto the previously folded down portions of the triangles and onto the adjacent portions of the diagonally folded lower corners.

3. The method of forming a paper radiator shield, comprising folding the top and the bottom of a rectangular sheet parallel to one another and in opposite directions; folding the upper corners diagonally inwardly to form triangular portions; folding the upper portions of said triangular portion above the plane of the sheet; folding said upstanding edge downwardly along a line parallel to the top line of fold, while re-folding said upper upstanding edge on said diagonal lines of fold; folding diagonally upwardly from the lower corners of the sheet, said diagonal lines of fold terminating above the lower edge of the triangular portions previously formed; applying adhesive to the tabs thus formed at either side, the adhesive area being shaped so as to be of lesser height adjacent the outer tips of the tabs than at the inner portions; and then folding the tabs inwardly toward one another.

4. The method of forming a paper radiator

shield, comprising folding the top and the bottom of a substantially rectangular blank of paper along parallel lines and in opposite directions; folding the upper corners diagonally toward one another to form triangular portions, 5 folding the upper portions of said triangular portion above the plane of the sheet; folding said upstanding edge downwardly along a line parallel to the top line of fold, while re-folding said upper upstanding edge on said diagonal lines of fold; folding the lower corners diagno-

nally toward one another to form triangular tabs projecting laterally of the blank, the last mentioned diagonal lines of fold terminating above the lower edges of said first-mentioned corners; applying adhesive to each of said tabs and of 5 increasing height toward the base of said triangular tabs, and thence folding said tabs toward one another; and then folding and inserting the lower portion of the thus folded blank beneath the previously folded portion. 10

BEN ALTHEIMER.
